(57) CLAIM

The ornamental design for a garment, as shown and described.

DESCRIPTION

FIG. 1 is a top front side perspective view of a garment showing my new design;

FIG. 2 is a front view of the garment;

FIG. 3 is a rear view of the garment;

FIG. 4 is a left side view of the garment;

FIG. 5 is a right side view of the garment;

FIG. 6 is a top view of the garment; and,

FIG. 7 is a bottom view of the garment.

The broken lines shown adjacent to the openings in the garment depict the boundaries of the claim that form no part of the claimed design. The broken lines within the boundary line shown in FIGS. 1 and 6 depict portions of the garment that form no part of the claimed design. The broken lines within the pocket depict stitching and form no part of the claimed design.

1 Claim, 6 Drawing Sheets

FIG. 1

FIG. 2

FIG. 3

FIG. 4

FIG. 5

FIG. 6

FIG. 7
